UNITED STATES PATENT OFFICE.

EDWARD E. EMMERICH, OF PARK RIDGE, ILLINOIS, ASSIGNOR TO CHAS. EMMERICH AND CO., OF CHICAGO, ILLINOIS, A CORPORATION OF ILLINOIS.

DESIGN FOR A TEXTILE FABRIC.

• 50,379.

Specification for Design.

Patented Feb. 27, 1917.

Application filed November 23, 1916. Serial No. 133,081. Term of patent 3½ years.

To all whom it may concern:

Be it known that I, EDWARD E. EMMERICH, a citizen of the United States, residing at Park Ridge, in the county of Cook and State of Illinois, have invented a new, original, and ornamental Design for Textile Fabrics, of which the following is a specification, reference being had to the accompanying drawing, forming a part hereof.

The figure of the drawing is a view of a portion of a textile fabric, embodying my new design.

Claim:

The ornamental design for a textile fabric, as shown.

EDWARD E. EMMERICH.
